UNITED STATES PATENT OFFICE.

KARL BALLOD, OF RIGA, RUSSIA.

CYCLE-LOCK.

No. 813,937.

Specification of Letters Patent.

Patented Feb. 27, 1906.

Application filed November 18, 1904. Serial No. 233,365.

To all whom it may concern:

Be it known that I, KARL BALLOD, a subject of the Emperor of Russia, residing at No. 39 Revaler street, Riga, Russia, have invented certain new and useful Improvements in Cycle-Locks; and I do hereby declare the following to be a full, clear, and exact description of the invention, such as will enable others skilled in the art to which it appertains to make and use the same.

This invention relates to a cycle-lock, whereby a movable lock is readily attached to a cycle-wheel, so as to prevent the use of the cycle by unauthorized persons.

15 To this end the cycle-lock consists of two sleeves adapted to be secured to the limbs of the front or rear fork and which sleeves are connected by a hinged bolt which can be secured by means of a catch device carried by 20 one of the sleeves, so that the said bolt passing through the spokes of the wheel prevents the forward movement of the same.

In order to enable the catch device to be automatically locked, a spring-actuated lever is provided having two noses, so that when the bolt is pressed from the outside against one of the noses the other nose releases a sliding piece, whereby the latter is, by means of a spring, moved in a horizontal direction, and its end engages in a slot in the bolt. The opening of the catch device is effected by means of a key the ward of which engages a notch in the sliding piece and returns the same to its original position.

35 In the accompanying drawings, Figure 1 is a front elevation showing the device in closed position in full lines and in its open position in dotted lines. Fig. 2 is a plan thereof. Fig. 3 shows the key. Fig. 4 is a front elevation showing the lock proper. Figs. 5, 40 6, and 7 are longitudinal sections through the lock proper at various positions of the sliding piece. Fig. 8 shows the mounting of the lock on the wheel-frame when the bolt is open, and Fig. 9 shows the same with the bolt closed.

The two main parts of the cycle-lock, A and B, are provided with eyes or clamps x, which may be tightened by means of a screw 50 and which are secured to each of the two limbs of the front or rear fork. To the part B is pivoted the bolt b, preferably consisting of a flat iron bar, and which bolt is, by means of a coil-spring u, pressed downward when the lock is open, assuming the position shown in Fig. 8.

The part A carries the lock proper inclosed in a casing a. A piece d, Figs. 5 to 7, has a slot r, so as to be free to slide in a horizontal direction relative to the stationary pin O². 60 One end i of this sliding piece is so formed that it can pass through an opening in the end of the lock-casing. Upon a second pin O' is pivotally mounted a lever e, one nose f of which in the lowest position of the lever, 65 Figs. 5 and 6, comes over the upper edge of the side of the lock-casing, while the other nose g in the same position of the lever lies in front of a ledge h on the sliding piece d. The lever e is engaged by the spring S, which is secured to the top of the casing. When the bolt b is swung down into the position shown in dotted lines in Fig. 1, the parts of the lock are in the position shown in Fig. 5. When this bolt is swung up into the position shown in full lines in Fig. 1, the end of it strikes the nose f of the lever e, lifting it against the tension of the spring S. When the nose g of the lever e releases the ledge h of the sliding piece d, the latter by the action of the spring q, bearing against the projection K on the sliding piece d, is moved to the right. In this movement the forward part i of the sliding piece d passes through a suitable opening in the side of the casing and at the same time into a slot 75 in the bolt b, so that the latter is secured in this position. To open the lock, a key p is introduced, the ward of which enters a notch in the sliding piece d and draws said piece back against the tension of the spring q to the position shown in Fig. 6. As soon as the ledge h of the sliding piece d has slid past beneath the nose g of the lever the lever e is pressed downward under the action of the spring S, so that the nose g, Figs. 5 and 6, lies in front of the 80 ledge h and prevents the movement of the sliding piece d by the action of the spring q. As soon as the bolt b is released by reason of the part i of the sliding piece d leaving the slot in the bolt it turns downward around the 85 pin O³ under the action of the spring u and lies against one arm of the fork, as shown in Fig. 8, so that when the wheel is rotating the bolt cannot come into contact with the wheel rim. After use the swinging cover c can be 90 brought back into the closed position, as shown in Fig. 5.

Having thus described my invention, what I claim as new, and desire to secure by Letters Patent, is—

110 1. A cycle-lock comprising two clamps adapted to be attached to the bars of the

- frame of a cycle, a spring-actuated bolt pivoted on one of said clamps, a casing containing a lock carried by the other clamp and a swinging attachment to said casing, said lock being provided with spring-actuated means for holding said bolt when swung into contact therewith, and with means for holding said lock open after it has been opened by a key, substantially as described.
- 10 2. A cycle-lock comprising two clamps adapted to be secured to the bars of the frame of a cycle, a swinging bolt pivotally attached to one of said clamps, a spring tending to swing said bolt out of contact with the cycle-
15 wheel, a casing provided with a lock carried by the other clamp, said casing being provided with a swinging extension, and spring-actuated means in said lock for automatically engaging and locking said bolt when the latter is swung up into contact therewith, and spring-actuated means for holding said lock open after it has been opened by a key, substantially as described.
- 20

3. A cycle-lock comprising two clamps adapted to be secured to the bars of the frame of a cycle, a slotted bolt pivotally connected to one of said clamps, a spring engaging said bolt and normally tending to hold it out of contact with the cycle-wheel, a casing, provided with a swinging extension, carried by the other clamp, a lock in said casing, a spring-actuated sliding piece provided with a projection, the end of said sliding piece being adapted to engage the slot in said bolt and a spring-actuated pivoted piece provided with a projection adapted to engage the projection on said sliding piece and hold the lock open after it has been opened by a key, substantially as described.

In testimony whereof I affix my signature in presence of two witnesses.

KARL BALLOD.
